Attorney

UNITED STATES PATENT OFFICE

HARRY GREENBERG, OF DOVER, NEW JERSEY

WORK-HOLDING IMPLEMENT

Application filed May 11, 1929. Serial No. 362,438.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a work holding implement especially applicable in soldering socket members.

In certain classes of articles, socket members are made in two parts because of manufacturing expediency or difference in metals. The particular employment of the socket member, as in fuse and detonator casings for projectiles, requires precision in establishing the connection between the parts of the socket and it is the purpose of this invention to provide an implement which will permit a rapid preparation of these parts for soldering.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing 30 which is a longitudinal sectional view of the implement with a socket in position for soldering.

Referring to the drawing by numerals of reference:

35 The implement consists of a handle 5 in which is secured a stepped blade 6 forming a threaded base 7, an intermediate shoulder 8 and an extended neck 9. The shoulder and the neck are of a form and length appropriate 40 for the respective support of the two elements 10 and 11 of different diameters of a socket member. The open end of the small element 11 is formed with an external annular flange 12 supportingly engaged by an internal flange 45 13 on the adjoining end of the large element 10. The remote end of the element 10 is also formed with an external flange 14 for supporting engagement by the flange 15 of a coupling nut 16 securable to the threaded base 7.

50 The threaded bore of the nut is slightly

greater than the flange 15 so that the nut may be freely slipped over the socket member and securely hold the elements 10 and 11 of the socket member in position on the blade.

55 The positioning of the socket elements and the nut on the blade may be performed individually or collectively. In either event the connection at the overlapping flanges which is the point of soldering will be accurately determined with respect to the axis of the socket.

60 In the preferred embodiment of the invention the length of the shoulder 8 and the neck 9 is so related to the length of the socket elements to be placed thereon that respective clearances 17 and 18 are present.

65 I claim:

A work holding implement including a handle, a blade secured to the handle and 70 formed in a series of steps, the outer steps adapted to position socket members, and a coupling securable to the largest step and having an internal flange spaced from the adjacent step.

75 HARRY GREENBERG.
